APPARATUS FOR HEATING FLUIDS

Herbert P. Dayton, Baytown, and Conrad H. Kol-
lenberg, Goose Creek, Tex., assignors to Stand-
ard Oil Development Company, a corporation
of Delaware

Application October 30, 1944, Serial No. 560,964

9 Claims. (Cl. 122—250)

1

The present invention is directed to an apparatus suitable for heating fluids, and more particularly to a heater adapted for heating hydrocarbon oils containing finely divided solid in suspension therein.

The device of the present invention is particularly suitable for cracking petroleum oils while using the suspensoid technique, wherein a finely divided catalyst is suspended in the oil and the suspension then forced through a heating coil. It is often desirable to conduct the cracking operation with the oil in a vapor phase, and if the conduit through which the oil is forced to flow contains abrupt turns, there is a decided tendency for the solid material to be thrown to the outside of the turn by centrifugal force, with resultant rapid erosion of the apparatus at the turns. By employing the apparatus of the present invention, higher concentration of finely divided solid catalyst may be employed (with resulting improved cracking) than in the usual return-bend type of coil, since the erosive action is distributed with desirable results over the entire coil rather than in the sharp return-bends.

The device of the present invention may be briefly described as involving a coil through which the material to be heated is caused to flow. The coil comprises a number of sections having the ends joined together in such a way that they may be readily connected or disconnected, while the furnace is provided with means arranged to shield the points of connection of the sections from the direct action of the combustion gases in the furnace used for heating the coil. The coil is arranged in the furnace so that the portion of the coil subject to the more severe eroding action of the suspensoid is heated to a higher temperature than the remainder of the coil. In those portions of the coil subjected to the highest temperatures, coke or carbonaceous solid material is more likely to form and the eroding effect of the finely divided solid is utilized to remove the coke or carbonaceous material from the coil.

Other objects and advantages of the present invention may be seen from the following description taken with the drawing, in which:

Fig. 1 is an elevation partly in section of an embodiment of the present invention;

Fig. 2 is a view along line II—II of Fig. 1;

Fig. 3 is an elevation of another embodiment of the present invention;

Fig. 4 is a section taken along IV—IV of Fig. 3;

Fig. 5 is a top view, with parts cut away, of another embodiment of the present invention.

2

The embodiment of Fig. 5 is generally similar in elevation to the embodiment of Figs. 1 and 2.

Figure 5A is an elevation partly in section of the embodiment of Figure 5.

Fig. 6 is a top view, with parts cut away, of another embodiment of the present invention. The embodiment of Fig. 6 is generally similar to that of the embodiment of Figs. 1 and 2.

Figure 6A is an elevation partly in section of the embodiment of Figure 6.

Figure 7 is an elevation partly in section of a still further embodiment of the present invention; and

Figure 8 is a view taken along line V—V of Fig. 7.

In the description of the several figures of the drawing, corresponding numerals will be employed to designate corresponding parts.

Turning now specifically to the drawing, and first to Fig. 1, a foundation 11 is arranged to support a furnace wall 12 having a generally cylindrical shape and formed of a suitable refractory material. Concentrically arranged within wall 12 is a second wall 13, having a generally cylindrical shape and spaced a substantial distance within wall 12 to define an annulus 14, which serves as a passage for the combustion gases of the furnace. A helical coil 15, made up of a plurality of sections 16, with each section bent 20 through an angle of 180° and the ends of the sections secured together by flanges 17 to form fluid-tight joints, is arranged around the inner furnace wall 13 and is supported thereby. The furnace is provided with a floor 19 constructed of a suitable refractory material. The floor is pierced by a plurality of ports 20, with a burner 21 arranged in each port and a conduit 22 arranged to supply each burner with a suitable combustion mixture. The burners are directed 25 upwardly to allow the direction of flow of the combustion gases to be substantially parallel with the longitudinal axis of the coil 15 as well as with the walls 12 and 13. The annulus 14 discharges 30 through an upper zone 23, defined by shell 24. Shell 24 is arranged to direct the hot gases through a preheating zone 25, containing tubes 26, and subsequently discharges the gases into stack 27.

While the inner furnace wall 13 has been described as having a generally cylindrical shape, the wall departs slightly from such a shape in order to prevent flanges 17 from coming directly into contact with the hot combustion gases filling space 14. Member 13 is conveniently constructed in two arcuate sections 28 and 29, with each arcuate section extending through substan-

tially less than 180°, and the ends of arcuate section 28 joined to straight wall sections 30 extending outwardly from the ends of section 28 and beyond helical coil 15. Similarly, the ends of arcuate section 29 are secured to straight sections 31 extending outwardly beyond helical coil 15. The ends of the sections 30 and 31 are joined by sections 32 extending at right angles to sections 30 and 31. Each wall section comprising units 30, 31 and 32 may be said to form an 10 outset section to shield flanges 17 from the combustion gases. It will be understood that walls 30 and 31 are pierced by a plurality of ports or openings to allow the passage of the turns of helical coil 15 through said walls.

The two outset sections comprising walls 30, 31 and 32 and spaced approximately 180° apart serve as the supporting means for coil 15. In the drawing the walls are shown as constructed of refractory material and pierced by ports through which the coil extends with each turn of the coil resting directly on the refractory of which these outset portions of the wall are formed. It will be understood that, if desired, metallic hangers may be used to suspend the coil from wall 13 and the ports in the outset portions may be made substantially larger than the outside diameter of the coil, with the space between the openings in the outset portion of the wall and the coil filled by a suitable plugging or calking material to prevent direct contact of the hot gases from space 14 with the flanges 17.

In suspensoid cracking operations it is conventional to vaporize a hydrocarbon feed stock and admix finely divided solid therewith to form a suspension, and pass the suspension through a heating coil. In the drawing either liquid or vaporized hydrocarbon containing the finely divided solid catalyst may be passed via inlet 33 into the lower end of coil 15, caused to flow in a continuous manner through the coil and removed from the upper end thereof via outlet line 34. It will be understood that the apparatus employed for preheating the oil and for forming a mixture of suspensoid in the vaporized oil is conventional to the art, suitable apparatus being disclosed, for example in U. S. Patents No. 2,319,710 and No. 2,322,070, issued to R. K. Stratford and R. H. Smith on May 18, 1943, and June 15, 1943, and accordingly such apparatus is not shown in the description of the furnace of the present invention. Similarly, the subsequent treatment of the mixture of thermally treated oil and suspensoid is conventional to the art and is not shown in the drawing.

When it is desired to disconnect the several sections comprising the heating coil, flanges 17 may be disconnected and the coils moved outwardly into space 14 until the ends thereof are free from walls 30 and 31. It is preferable to employ as coupling means 17 flanges which may be removed from the ends of the coil so that the ends of the coil may pass through openings of substantially no greater size than those through which the sections of the coil pass when the coil is intact. If such removable flanges are employed, it will be necessary to disturb the refractory material very little, if at all, in order to dismantle the coil 15. However, if desired, the flange members may be fastened directly to section 16 and portions of the refractory material removed from walls 30 and 31 to allow the passage of the flange members therethrough in dismantling the helical coil, and upon reassembling the coil such openings may be filled with refractory material.

It will be evident that the outside portion of coil 15 receives a substantially greater amount of heat than the inside portion because of the exposure of the outside portion to the radiant energy received from the combustion mixture. In cracking operations, coke and carbonaceous material result at the high temperatures to which the hydrocarbon material being cracked is exposed, and such materials are deposited to a greater extent in those portions of the apparatus subjected to the higher temperatures. When employing the furnace of the present invention for cracking oils there will be a tendency for substantially greater portions of coke and carbonaceous solids to deposit on the outer rather than on the inner side of the interior surface of the coil. The solid material conventionally employed in cracking operations has a density many times greater than the vaporized hydrocarbon preferably employed as the suspending medium, and the flow of the suspensoid through the coil causes a centrifugal force to be exerted on the solid material which forces it to the outside of the helical coil. Accordingly, that portion of the coil in which there is a greater tendency to form coke is subjected to a greater erosive effect from the suspensoid than is the remainder of the coil, and the scouring effect produced by the solid material as it passes through the coil is, at least in a substantial measure, proportioned to the tendency of coke to deposit on the surface of the heating coil.

It is to be understood that the present invention is not limited to the use of any specific dimensions in the construction of the device nor to the thermal treatment of any specific charging stock nor to any specific charging rate. It will be found, for example, that the diameter of the coil may be varied from less than 20 to greater than 60 feet, as desired. It will also be found that the furnace may be employed for thermally treating a substantial range of hydrocarbons at any desired charging rate. It is preferred, however, to employ a hydrocarbon in the gas oil boiling range as a charging stock and to pass the suspension of vapors and catalyst through the coil at a rate in the order of 100 to 200 feet per second.

Although for purposes of description the apparatus has been described as circular in cross section, it is to be understood that the exterior wall of the apparatus may be square or even rectangular in shape. Preferably, however, the outer wall should be substantially parallel to the curvature of the heating coil, since the greater part of the heat imparted to the fluid flowing in the coil is obtained by radiation from the flame and from the outside refractory wall.

The embodiment of Figs. 3 and 4 may be similar to that of Figs. 1 and 2 in the arrangement of the foundation and floor. The coil 15 is made up of sections, with each section defining an arc of approximately 180° and the ends of the sections secured together by flange members 17 in exactly the same way as the embodiment of Figs. 1 and 2.

The outer wall in the embodiment of Fig. 3 is comprised of arcuate sections 35 and 36, with each section defining an arc somewhat less than 180°. The inner wall is comprised of sections 28 and 29 extending through an angle of somewhat less than 180° and corresponding to the sections designated by the identical numbers in the embodiment of Figs. 1 and 2. Adjacent ends of sections 28 and 35 are connected by the straight wall sections 37-37, and the adjacent ends of sections

29 and 36 are connected together by straight wall sections 38-38. Sections 28, 35 and 37 define a combustion zone, and similarly sections 29, 36 and 38 define a second combustion zone. The two combustion zones are generally arcuate in section and are designated as 14'-14', with the two zones defining substantially the same space as defined by combustion zone 14 of the embodiment shown in Figs. 1 and 2. In the embodiment of Fig. 3, burners 21 are arranged in each combustion zone 14' with the combustion gases directed substantially parallel to the longitudinal axis of coil 15. The upper ends of the combustion zones 14'-14' discharge into a shell 24', which defines a preheating section 25 containing coils 26 and discharges into stack 27.

The embodiment of Figs. 3 and 4 conveniently allows the circulation of air adjacent the flange members 17 so that these members may be at a temperature substantially below the temperature of the refractory walls within combustion zones 14'-14'. In this embodiment the flange members may be inspected while the furnace is in operation and maintenance and repair operations may be carried out on this part of the apparatus before the entire furnace has been cooled. It will be understood that the flanges 17 of the embodiment of Figs. 3 and 4 may either be removable to allow the convenient removal of the ends of coil section 16 through walls 37 and 38, or alternatively flange member 17 may be secured to the ends of section 16 in a more permanent manner and the openings in walls 37 and 38 through which coil sections 16 pass may be enlarged to allow the passage of the flange members when removing or replacing section 16 of the coil.

Another embodiment of the present invention is shown in Fig. 5. Fig. 5 is a top view, with parts cut away, to give a view generally similar to the top view shown in Fig. 2 of the embodiment illustrated in Figs. 1 and 2.

In Fig. 5 a heating coil 40 is made up of 60° sections with six sections making up a complete turn of the coil. The ends of the sections are connected together by flanges 41. The combustion zone is defined by an inner wall comprising 6 arcuate segments 42 with the ends of the arcuate segments connected together by straight wall sections 43 and 44. An outer tubular wall 45 is spaced a substantial distance away from the inner wall and cooperates therewith to define a combustion zone 46, in which burners 21 are arranged to direct combustion gases substantially parallel with the longitudinal axis of coil 40, as well as parallel to the longitudinal axis of outer wall 45, and the inner wall is comprised of sections 42, 43 and 44. It will be understood that straight wall sections 43 serve to support the segments of heating coil 40.

The embodiment of Fig. 5 is particularly adapted for large furnaces wherein the heating coil may have a diameter as great as 60 feet. The division of each turn of the heating coil into at least 6 segments, with the ends of each segment supported, allows the segments to be made in dimensions which allow them to be readily handled and in addition provide adequate support for the segments in the furnace. In Figure 5A it will be seen that an elevation of the embodiment of Figure 5 is given and the general arrangement of flow of the oil through line 33 and coil 40 is similar to that described with respect to Figure 1. In this particular embodiment the ends of the six sections making up a complete turn of the coil

are enclosed by wall sections 43 and 44 which isolate flanges 41 from the combustion section 46. It will be seen that the arcuate segments 42 and the straight wall sections 43 and 44 are connected to define an inner wall. The inner wall and the outer tubular wall 45 define a combustion zone 46.

It is usually desirable to construct the heating coil of the furnace of the present invention with a circular cross section and a vertical axis.

It is also usually desirable to construct the inner furnace wall and the outer furnace wall as tubular members with a generally circular shape. If desired, however, the axis of the heating coil may be arranged at an angle to the vertical and the plan view of the coil may be in the form of a closed curve which is not a circle. If the plan view of the heating coil is formed into a non-circular shape, it is desirable that it be generally oval in cross section and that the largest dimension across the oval be no greater than 1½ times the smallest dimension across the oval.

Fig. 6 is a top view, with parts cut away, of another embodiment of the present invention.

The elevational view of this embodiment would be generally similar to the elevational view of Fig. 1. It may be pointed out that the principal difference between the embodiment of Fig. 6 and that of Figs. 1 and 2 is that in Fig. 6 the heating coil is, in plan view, in the form of an oval and each turn is divided into 4 sections, whereas in the embodiment of Figs. 1 and 2 the heating coil is of a circular section and each complete turn is divided into 2 parts.

In Fig. 6 a heating coil 51 is shown as comprising 4 sections for every complete turn with flanges 52 arranged to connect the several sections together to form a complete coil. It will be understood that in this embodiment of the invention as in precedingly described embodiments, the heating coil will preferably comprise a substantial number of complete turns. An inner wall is defined by arcuate sections 53 connected together by straight wall sections 54 and 55 arranged with the arcuate sections 53 within the heating coil and straight wall sections 54 and 55 forming outset portions to shield the connecting flanges of the heating coil from direct contact with combustion gases. An oval shape outer wall 56 is provided which follows the same general shape as coil 51 and the inner wall of the furnace and co-operates with the inner wall to define a combustion zone. Burners 21 are arranged in the combustion zone 57 to direct the combustion gases substantially parallel to the vertical axis of the heating coil 51 and the inner furnace wall. In Figure 6A it will be seen that the outer oval shaped wall follows the general configuration of wall 51 and the inner wall of the furnace to define a combustion zone 57. The inner wall is divided into arcuate sections 53 which are connected by straight wall sections 54 and 55 with the arcuate sections 53 within the heating coil, straight wall sections 54 and 55 forming outset portions to shield flanges 52 from direct contact with the combustion gases in zone 57.

When the heating coil of the furnace is formed in an oval shape as in Fig. 6, it is desirable for the completed coil to define a pattern containing only smooth, gradual curves. In general, it will be found desirable to have the longest axis of the oval no greater than 1.5 times the shortest axis.

The embodiment of Figures 7 and 8 may be generally similar to that of Figures 3 and 4 with

the exception that the embodiment of Figures 7 and 8 show a structure generally oval in shape. In Figures 7 and 8 the coil 60 is made up of sections with each section defining an arc somewhat less than 180°. The outer wall of the embodiment of Figure 7 comprises arcuate sections 61 and 62 with each section defining an arc somewhat less than 180°. The inner wall is comprised of sections 63 and 64 extending at an angle of somewhat less than 180°. Adjacent ends of sections 61 and 63 are connected by straight wall sections 65—65 and adjacent ends of sections 62 and 64 are connected by straight wall sections 66—66. Sections 61, 63, and 65 define a combustion zone 67' and, similarly, sections 62, 64, and 66 define a second combustion zone 67'. The two combustion zones are generally arcuate in section and are designated as 67'—67'. In the embodiment of Figure 7, burners 21 are arranged in each combustion zone 67' with the combustion gases directed substantially parallel to the longitudinal axis of wall 60. The upper ends of the combustion zones 67'—67' discharge into a shell 24 which defines a preheating section 25 containing coil 26 and from thence discharges into stack 27.

The embodiment of Figures 7 and 8, similar to the embodiment of Figures 3 and 4, conveniently allows the circulation of air adjacent the flange members 68 so that these members may be at a temperature substantially below the temperature of the refractory walls within combustion zones 67'—67'. It will be understood that, like the embodiment of Figures 3 and 4, the flanges 68 of Figures 7 and 8 may either be removable to allow the convenient removal of the ends of coil 60 through walls 65 and 66, or alternatively, flange members 68 may be secured to the ends of sections 60 in a more permanent manner and the openings in walls 65 and 66 through which coil sections 60 are passed may be enlarged to allow the passage of the flange members when removing or replacing sections of the coil.

Although for purposes of description the apparatus has been described as circular in cross section, it is to be understood that the exterior wall of the apparatus may be square or even rectangular in shape. Preferably, however, the outer wall should be substantially parallel to the curvature of the heating coil, since the greater part of the heat imparted to the fluid flowing in the coil is obtained by radiation from the flame and from the outside refractory wall.

It will be understood that the number of sections required to be joined together to make a complete turn of the heating coil may be varied over a substantial range. Usually it will be found convenient to use a number ranging from 2 to 6 sections to make a complete turn. That is to say, if the cross section of the heating coil is circular, the sections may conveniently be formed to describe arcs ranging from 60° to 180° and may, of course, include arcs of 90° or 120°. Similarly, if the cross section of the heating coil is in the shape of a closed curve, which is non-circular, it will be found convenient to employ from 2 to 6 sections to make up a complete turn of the coil. In general, the larger the cross section of the furnace, the greater will be the number of sections employed to make a complete turn of the heating coil with the sections equally proportioned.

In the elevation of the embodiments of Figs. 1 and 3, the heating coil has been shown as helical. While this is a preferred shape of the coil, it will

be understood that the coil is by no means restricted to a helical shape, but that if desired the space between the turns of the coil may be either greater or less than the spaces between the turns of a helical coil.

Having fully described the present invention, what we desire to claim is:

1. An apparatus for heating fluids comprising, in combination, a plurality of sections of tubing each defining an arc of not more than 180°, releasable flange means connecting together the tube sections to form a coil comprising a plurality of turns, a first furnace wall comprising an arcuate section with the radius of the arcuate section smaller than the radius of the coil and arranged concentric with the coil, a second furnace wall comprising an arcuate section having a substantially greater radius than the radius of the coil and concentric therewith, wall sections co-operating with the first and second furnace wall to define a combustion zone excluding the flanges but including a major portion of at least some of said tube sections, and means supplying air and fuel to the combustion zone and directing the resulting flames and hot gases in a line parallel with the axis of the coil.

2. An apparatus for heating fluids comprising, in combination, a plurality of sections of tubing each defining an arc of not more than 180°, removable flange members securing ends of the tubular sections together to define a coil comprising a plurality of turns, an outer furnace wall member comprising arcuate sections having a radius substantially greater than the radius of the coil and concentric therewith, an inner wall member comprising arcuate sections with a radius smaller than the radius of the coil and concentric therewith, non-arcuate sections in communication with the arcuate sections of the inner member, the arcuate and non-arcuate members of the inner structure co-operating with the outer structure to define a combustion zone including the major portion of the coil but excluding the flange members and maintaining said flange members in fluid communication with the space defined within the inner arcuate members, and means for introducing a combustible mixture within the combustion zone and for directing resulting flames and gases in a direction parallel with the axis of the coil.

3. An apparatus for heating fluids comprising, in combination, a plurality of tubular members each defining an arc of approximately 180°, removable flange members securing together ends of the tubular members to form a coil comprising a plurality of turns and having a vertical axis, an outer furnace wall member comprising a cylindrical refractory wall having a radius substantially greater than the radius of the coil and concentric with the coil, an inner wall member comprising two arcuate portions each including less than 180° and with a radius less than the radius of the coil and concentric therewith, wall portions arranged to join together the adjacent ends of the inner arcuate members and to include in the space defined within the inner arcuate members the flange members joining together the tubular members and means arranged for introducing a combustible mixture into the space included between the inner and outer furnace wall members and to direct resulting flames and hot gases in the space parallel to the longitudinal axis of the coil.

4. An apparatus for heating fluids comprising, in combination, a plurality of tube sections each

defining an arc of 180°, removable flange members securing together ends of the tube members to define a coil with a vertical longitudinal axis, a first and second arcuate furnace wall member of the same radius and subtending equal arcs including less than 180°, said first and second arcuate members being concentric with the coil and having a radius substantially greater than the radius of the coil, a third and fourth arcuate furnace member subtending the same size arc as the first and second furnace members but having a radius less than the coil and arranged concentric therewith with the ends of the third member and the ends of the first member lying on a line and the ends of the fourth member and the ends of the second member lying on a line, wall members connecting together the adjacent ends of the first and third and second and fourth members to define two combustion zones and a third zone separating the combustion zones, the third zone including the flange members connecting together the tube members, and means for introducing a combustible mixture into each of the combustion zones and for directing the resulting flames and hot gases in the combustion zone parallel to the longitudinal axis of the coil.

5. An apparatus in accordance with claim 1 in which said coil is circular in plan view.

6. An apparatus in accordance with claim 1 in which said heating coil is oval in plan view.

7. An apparatus for heating fluids comprising, in combination, a plurality of sections of tubing each defining an arc not greater than 180°, releasable flange members connecting together the tube sections to form a heating coil, said heating coil having a vertical axis and including a plurality of complete turns with each complete turn in plan view being in the form of a closed curve symmetrical with respect to the axis of the coil, a combustion zone defined by wall sections parallel with the axis of the coil, said combustion zone including at least a portion of each complete turn and excluding all flange members, at least one of said wall sections being arcuate, within the coil and concentric therewith, at least another of the wall sections being arcuate, spaced

away from the coil and concentric therewith, and means for supplying a combustible mixture to said combustion zone and for directing the resulting flames and hot combustion gases parallel to the axis of the coil.

8. An apparatus in accordance with claim 7 in which the arcuate wall member within the coil is adjacent thereto and in which the combustible mixture is supplied to portions of the combustion zone adjacent the wall member spaced away from the coil.

9. An apparatus for heating fluids comprising, in combination, a plurality of sections of tubing each defining an arc not greater than 180°, releasable flange members connecting together the tube sections to form a heating coil, said heating coil having a vertical axis and including a plurality of complete turns with each complete turn in plan view being in the form of a closed curve symmetrical with respect to the axis of the coil, a combustion zone defined by wall members parallel with the axis of the coil and additional wall members also parallel with the axis of the coil and spaced from said wall members, said combustion zone enclosing at least a portion of each complete turn, said additional wall members excluding all flange members of said tube sections from said combustion zone, at least one of the wall members being arcuate, outside the coil, spaced away from the coil and concentric therewith and means for supplying combustible liquid to said combustion zone and for directing the resulting flames and hot combustion gases parallel to the axis of the coil.
